UNITED STATES PATENT OFFICE.

MICHELE N. SALVATI, DECEASED, LATE OF TURIN, ITALY, BY GUIDO BEER AND ARRIGO TEDESCO, JOINT EXECUTORS, OF TURIN, ITALY, ASSIGNEES TO SOCIETÀ ANONIMA STABILIMENTI BIAK, OF TURIN, ITALY, A COMPANY OF ITALY.

ARRANGEMENT FOR CONNECTING WOODEN RODS WITH METAL BARS IN AEROPLANE STRUCTURES.

1,325,805.

Specification of Letters Patent. Patented Dec. 23, 1919.

Application filed July 25, 1919. Serial No. 313,215.

To all whom it may concern:

Be it known that we, GUIDO BEER and ARRIGO TEDESCO, subjects of the King of Italy, and residents of Turin, Italy, joint executors of MICHELE N. SALVATI, deceased, late of Turin, Italy, do hereby declare that said MICHELE N. SALVATI did in his lifetime invent certain new and useful Arrangement for Connecting Wooden Rods with Metal Bars in Aeroplane Structures, of which the following is a specification.

It is known that advantages are secured by using in aeroplane structures metal bars instead of common wooden ones because of reduced weight and increased resistance thus obtained; on the other hand when using said metal bars difficulties are found in safely connecting the wooden rods with the metal bars.

This invention has for its object an arrangement allowing of reaching said purpose by simple means; according to this invention the metal bar web is provided at the points at which the wooden rod has to be connected, with a number of openings through which are inserted plates which are engaged with the web of said wooden rod, preferably by interposing between said plates and web the wooden blocks at present used for strengthening the wooden rod flanges at the places at which they do not bear on the metal bar.

The annexed drawing shows by way of example one construction of the arrangement according to this invention; Figure 1 is the side view of the wooden rod the metal bar being shown in section on line $x-x$ of Fig. 2 and Fig. 2 is the side view of the metal bar at the connecting point, the wooden rod being in section.

As shown in said figures the web 2 of wooden rod is provided with a suitable opening passed through by metal bar 1 which may have any required contour, the flanges 3 of said wooden rod bearing on the outer surfaces of flanges of metal bar 1, and said web 2 is provided near edges of said openings with strengthening wooden blocks 4 extending from a flange thereof to other one, as used at present.

In the construction illustrated the web of metal bar 1 is provided with an opening 5 larger than the whole thickness of web 2 and

blocks 4 and two plates 6 made of strong wood are inserted into said opening, one at 55 each side of web 2, the same being connected, by means of screws and gluing, with the block 4 adjacent thereto and thence with web 2 of the wooden rod.

Instead of a single opening 5 having such 60 a width as to overcome outer edges of blocks 4, the web of metal bar 1 may be provided with two separate openings each at one side of the web 2 and having a width corresponding with thickness of plate 6; further on 65 each side of web 2 of the wooden rod there may be arranged a plurality of plates 6.

In any case owing to plates 6 passing through web of metal bar and being strongly connected with the web of wooden rod, a safe 70 connection is obtained between wooden rods and metal bars, the direct transmission of stresses being thus obtained.

What we claim as the invention and desire to secure by United States Letters Patent 75 is:—

1. A connection for wooden rods and metal bars in aeroplane structures, comprising a metal bar having a web and flanges, a wooden rod having a web and flanges and provided with an opening in said web through which said metal bar passes, the flanges of said wooden rod bearing on outer surfaces of flanges of said metal bar, the web of said metal bar having an opening 80 at the crossing point of said rod and bar, and wooden plates inserted in said opening the same embracing said wooden rod web and being connected therewith.

2. A connection for wooden rods and 90 metal bars in aeroplane structures comprising a metal bar having a web and flanges, a wooden rod having a web and flanges and provided with an opening in said web through which said metal bar passes, the 95 flanges of said wooden rod bearing on the outer surfaces of flanges of said metal bar, strengthening blocks embracing said wooden rod web at the edges of said opening, the web of said metal bar having an opening 100 at the crossing point of said rod and bar, and wooden plates inserted in said opening the same embracing said blocks and being connected with them and with said web.

3. A connection for wooden rods and 105 metal bars in aeroplane structures, comprising

ing a metal bar having a web and flanges, a wooden rod having a web and flanges and provided with an opening in said web through which said metal bar passes, the 5 flanges of said wooden rod bearing on the outer surfaces of the flanges of said metal bar, the web of said metal bar having openings in register with outer edges of said wooden rod web, and wooden plates inserted

in said openings the same embracing said 10 wooden rod web and being connected therewith.

Signed at Turin, Italy, July 2, 1919.

GUIDO BEER,
ARRIGO TEDESCO,
Joint Executors of Michele N. Salvati, deceased.
